UNITED STATES PATENT OFFICE.

STEPHEN W. RATHBUN AND DANIEL R. KINLEY, OF MARION, IOWA.

PRINTER'S GALLEY.

SPECIFICATION forming part of Letters Patent No. 367,446, dated August 2, 1887.

Application filed October 15, 1886. Serial No. 216,324. (No model.)

To all whom it may concern:

Be it known that we, STEPHEN W. RATHBUN and DANIEL R. KINLEY, citizens of the United States, residing at Marion, in the county 5 of Linn and State of Iowa, have invented certain new and useful Improvements in Printers' Galleys, of which the following is a specification.

The object of our invention is to improve 10 the construction and simplify and facilitate the operation of a printer's galley; and the invention consists in connecting the movable side-sticks, foot stick, and quoin permanently with the body of the galley, and in the peculiar 15 construction and arrangement of the parts, as will be hereinafter fully set forth and described.

In the accompanying drawings, forming a 20 part of this specification, Figure 1 represents a plan view of the invention; Fig. 2, a side elevation of the same; Fig. 3, an end view thereof; Figs. 4 and 5, vertical sections of the quoin, showing different modes of attaching the same to the galley; and Fig. 6, a quoin provided 25 with a base-plate, whereby it may be secured to the galley.

Similar letters of reference indicate corresponding parts.

Our galley is constructed as follows: To one 30 side and end of a suitable plate, A, (preferably of brass,) are secured ledges B B'. Along the inner and lower side of these ledges is formed a groove, b, which is L-shaped in cross-section, as shown. The end of the side and 35 foot sticks C C' are so shaped as to correspond with this groove, having a lug, c, adapted to hold the stick from longitudinal movement, and at the same time allow the stick to slip freely sidewise along the ledge. The foot of the ledge 40 B' is provided with a recess corresponding to the thickness of the foot-stick, so that when the latter is turned around, as indicated by the dotted lines in Fig. 1, it is flush with the inner face of the ledge. This allows for the slipping 45 of matter out of the end of the galley, and also admits of a column of matter as long as the entire galley being held therein, when desirable, by making the length of the side-stick to correspond. To admit of the foot-stick turning 50 freely in its seat, the lug should be made round in cross-section, so as to serve as a pivot. A pin, e, prevents its slipping out at the end.

Near the open side of the galley are attached the quoins D D D by suitable pivots or studs, a a a. The quoin is made cam-shaped, and is 55 provided with a short projection at one side, to serve as a lever in turning it. This construction admits of the matter being locked in the galley without the use of extra wrenches or shooting-sticks or other separate apparatus, 60 and avoids the inconvenience and loss of time incident to the use of such devices, and especially the finding of them when mislaid. The stud a is fastened securely to the bottom plate of the galley by riveting or brazing, and a projecting flange at the top prevents the quoin from falling off when the galley is turned upside down.

Simple forms of attachment are shown in 70 Figs. 4 and 5. In the former the quoin is mounted loosely on a stud riveted to the bottom plate, and having a suitable head to hold the quoin from displacement. In the case of Fig. 5 the stud passes through a bushing, d, which is made a trifle longer than the vertical 75 thickness of the quoin, so that when the stud is riveted to the base-plate in the position shown in the figure the quoin is free to turn under the projecting head of the stud. All the parts of the galley are thus connected together, 80 and the common inconvenience and waste of time due to the accidental displacement of the several necessary parts of the galley are obviated.

The matter is locked for proving by simply 85 turning the quoins, as indicated in Fig. 1, and as quickly released. The foot-stick being adapted to slip freely the whole length of the galley, serves to support the type at that end whatever may be the length of the matter. 90

It is of course necessary that the stud which holds the quoin should be quite rigid and firmly secured to the base-plate at right angles thereto. As some skill would be required to do this in the case of the construction shown 95 in Figs. 4 and 5, and as it is desirable to render the quoin applicable to any galley, and by persons not specially skillful as mechanics, a modified construction is shown in Fig. 6, where the stud is attached to or forms a part of the 100 small base-plate A', having suitable holes, as shown, by which it is conveniently attached to the bottom plate of the galley. In this case the quoins and sticks might be furnished to

the printer separate from the galley proper. For the same reason it may be found desirable to substitute for the groove in the end ledge, B, the slotted guide-plates attached to the side-
5 stick and held in place by suitable studs, as indicated in Fig. 1. In the use of the groove in the ledge it is of course not essential that the groove should be of the precise form shown, a T-shaped or common dovetail groove being
10 obvious substitutes therefor.

Having thus briefly described our invention, what we claim as new, and desire to secure by Letters Patent, is—

1. In a printer's galley having but one side and one end ledge, the combination of the laterally-movable side and foot sticks C C', permanently attached to the galley, and quoins D D', permanently and eccentrically pivoted to

the galley-plate, and having each a lever formed integral with the rest of the quoin, substantially as and for the purpose set forth. 20

2. In a printer's galley, the ledge B', having groove b, and an offset near the lower end corresponding to the thickness of the foot-stick C, in combination with the foot-stick, having 25 a lug corresponding to the groove and engaging therewith and held from displacement by a pin, e, substantially as and for the purpose specified.

In testimony whereof we affix our signatures 30 in presence of two witnesses.

STEPHEN W. RATHBUN.

DANIEL R. KINLEY.
